UNITED STATES PATENT OFFICE.

BENJAMIN F. COURTRIGHT, OF EAST SAGINAW, MICHIGAN.

HYDRANT AND STREET-WASHER.

SPECIFICATION forming part of Letters Patent No. 332,137, dated December 8, 1885.

Application filed May 1, 1885. Serial No. 164,094. (No model.)

To all whom it may concern:

Be it known that I, B. F. COURTRIGHT, a citizen of the United States, and a resident of East Saginaw, in the county of Saginaw and State of Michigan, have invented certain new and useful Improvements in Hydrants and Street-Washers; and I do hereby declare that the following is a full, clear, and exact description of the invention, which will enable others skilled in the art to which it appertains to make and use the same, reference being had to the accompanying drawings, which form a part of this specification.

My invention relates to that class of hydrants and street-washers which are provided with a waste-vent or relief-port adapted to permit the escape of the water remaining in the discharge-pipe after the entry-port or inlet-valve of the pipe has been closed, the valve controlling the said waste-vent being connected to the main valve-rod in such a manner that the latter will close the waste-vent when opening the entry-port and open the waste-vent when closing the said port.

The object of my invention is to produce a combined hydrant and street-washer of the above-described class, which shall be inexpensive to manufacture and simple and efficient in operation; and to that end it consists in the improved construction and combination of parts, which will be hereinafter fully described, and pointed out in the claims.

Referring to the annexed drawings, Figure 1 is a vertical sectional view of my improved combined hydrant and street-washer, taken on the plane indicated by line $x-x$ in Fig. 2. Fig. 2 is a rear elevation of the lower part of the hydrant. Fig. 3 is a side view of the same. Fig. 4 is a transverse sectional view taken on line $y-y$, Fig. 1; and Fig. 5 is a longitudinal vertical sectional view of the upper part of the device, showing the nozzle or spout reversed to adapt the hydrant for use as a street-washer.

The same letters indicate corresponding parts in all the figures.

Referring to the several parts by letter, A represents the barrel or cylinder of the hydrant, preferably of one-inch iron pipe, and having screwed upon its upper end the top B, of which the spout or nozzle B' forms a part, being cast integral therewith, the free end of

the spout B' being provided with an exterior screw-thread to admit of a hose being connected thereto. C indicates the upper operating end of the valve-rod, being provided with the annular shoulder or projection c, which rests and turns upon a corresponding shoulder, b, in the upper end of the top B, so as to hold the shaft C in position. A gasket, c', surrounds the shaft C and rests upon the annular projection c, thereby preventing any leakage of water through the top of the hydrant, a screw-cap, B², closing the upper end of the hydrant and serving to hold the washer and the shaft itself in position. The upper end of this screw-cap is made square, in order that it may be readily removed when it is necessary to replace the washer with a new one. The upper projecting end of the shaft C is also squared, to adapt it to receive a suitable hand-wheel, by means of which the shaft C, and through it the valve-rod D, are operated. The lower hollow end of the shaft C is provided with an interior left-handed screw-thread, b², so that when the shaft C is turned to the right by its hand-wheel the valve-rod D will be lowered, for the purpose hereinafter set forth.

D represents the valve-rod, which is provided at its upper end with an exterior left-handed screw-thread to admit it to work within the lower hollow threaded end of the operating-shaft C.

F indicates the casting composing the lower part of the hydrant, the said casting being provided at its upper end with an interior screw-thread to adapt it to be secured upon the lower end of the barrel or cylinder of the hydrant, a screw, a², tapped through the screw-threaded ends, serving to prevent the barrel A from screwing out of the part F. To the lower end of the part F is screwed a hemispherical casting, F', provided at its bottom with the exterior screw-threaded inlet pipe or neck, f', and prevented from unscrewing from the part F by a small screw, f², which is tapped through the screw-threaded flanges, as shown in Fig. 2.

Within the spherical valve-chamber G works the spherical flexible valve H, which consists of a solid rubber ball having a central opening, through which the lower screw-threaded end of the valve-rod passes, the ball being firmly secured by means of small rivets or

screws *i* to a concave receptacle or basin *I*, within which its lower part rests, the said basin being cast with a nut, *J*, on its lower exterior side, and both the nut and basin being provided with an aperture which registers with the central aperture, *h*, of the ball-valve when the said valve is secured upon the basin *I* by means of the small screws *i*, passing through suitable apertures in the said basin, by which arrangement the ball is held firmly against the pressure of the water when the valve-rod is lowered, and the valve thus removed from its seat *h*² to admit the water, which enters through *f'* from the street-main, to pass up and out of the hydrant. The annular convex valve-seat *h*² is semi-spherical in cross-section, as shown in Fig. 1, the rubber ball-valve pressing closely around the same when the valve is closed, while, when the valve is open, the valve-seat is left perfectly clear, this arrangement preventing any sand, gravel, or other sediment from lodging on the valve-seat to prevent its working. When the upper side of the ball-valve, which fits upon the valve-seat, becomes worn through long use, the valve may be raised a little by merely turning the nut *J* to the right, while, when the ball becomes completely worn out, it can be replaced at a cost of a few cents.

Secured at one end to the rod *D* at a point a little above the valve-chamber *G*, is a transverse rod, *K*, working in a suitable opening or recess in the casting *F*, and having secured to its outer end the lower screw-threaded end of a vertical auxiliary valve-rod, *L*, the upper end of which passes up through a vertical aperture, *f'*, in the casting *F*, constituting the waste-vent or relief-port, and has secured upon its screw-threaded extremity adjustably the auxiliary rubber ball-valve *N*, which is exactly similar in construction to the main valve *H*, having the basin *N'* and nut *n* and rivets or screws *n'*, the rod *L* being of such a length that when the valve-rod *D* is lowered to open the entry-port the auxiliary valve *N* will bear firmly upon its seat *O*, which is of the same shape as the seat of the main valve, and is therefore always clear of sediment and in working order. The auxiliary valve-rod *L*, which works through the vertical aperture *f'* in the casting *F*, constituting the waste-vent, is provided with the three external longitudinal grooves, *l*, (shown in Fig. 1 of the drawings,) so that when the said rod is elevated by the raising of the main valve-rod *D*, so as to lift the auxiliary valve *N* up from its seat, the water remaining in the barrel of the hydrant above the valve *H*, which is closed by this movement, will by its own gravity pass through the longitudinal grooves *l* out of the opening *f'*, a cap, *M*, having the ports or vents *m*, through which the waste water escapes, being secured, by means of the screws *f'*, to the casting *F* upon the rear upper side thereof, and extends above and around the auxiliary valve *N*, so as to protect it from injury. The three corners or strips left be-

tween the three longitudinal grooves of the auxiliary valve-rod serve to prevent the rod from shaking or moving from side to side in the aperture *f'*, through which it passes.

P P', Fig. 3, indicate screw-plugs, which close suitable openings in the casting *F*, opening, respectively, immediately above the valve-chamber *G*, to enable the arm *K* to be secured upon the valve-rod *D*, and into the recess in which the arm *K* works, to enable the lower end of the valve-rod *L* to be screwed into the outer end of said arm.

In Fig. 5 the outlet-nozzle *B'* is shown reversed or turned upward to adapt the hydrant for use as a street-washer, a metal plate, *Q*, being in this case placed upon the top of the device, being provided with suitable apertures, through which the upturned end of the nozzle and the top of the shaft *C* project.

The operation of my improved combined hydrant and street-washer is as follows: The hydrant is connected with the service-pipe or street-main by the exterior screw-threaded neck, *f'*, and to permit the water to flow up through the hydrant and out of the spout *B'* the hand-wheel on the upper end of the shaft *C* is turned to the right, thereby lowering the valve-rod *D* and removing the valve *H* from its seat, this movement, also, through the arm *K* and auxiliary valve-rod *L*, closing the waste-vent by depressing the valve *N* upon its seat *O*. The water now flows, through the valve-chamber *G*, up through the barrel of the hydrant and out at the spout *B'*, the closed auxiliary valve *N* preventing the escape of any water through the waste-vent. To stop the flow of water, the hand-wheel is turned to the left, thereby raising the valve-rod *D* and pressing the main valve *H* firmly upon its seat, which cuts off the flow of water from the service-pipe or main, this upward movement of the valve-rod also operating to raise the arm *K*, auxiliary valve-rod *L*, and valve *N*, thereby permitting the escape of the water remaining in the hydrant-barrel above the inlet-valve *H* through the waste-vent *f'*.

The device may, if desired, be inclosed in a casing having a cover, so as to prevent any dirt surrounding the device from entering the waste-vents.

From the foregoing description, taken in connection with the accompanying drawings, the construction and operation of my improved combined hydrant and street-washer will be readily understood without requiring further explanation.

It will be seen that my invention is simple in construction, and is therefore not liable to get out of order, while at the same time it is very efficient in operation and inexpensive to manufacture. It will also be seen that there is no leather packing employed, which is liable to dry up and get hard, thereby preventing the hydrant from working smoothly.

Having thus described my invention, what I claim, and desire to secure by Letters Patent of the United States, is—

1. In a hydrant and street washer having a suitable upper part, the combination, with a tube-shaped lower part having a perforation through its side, and an inner recessed longitudinal projection at one side above the valve-chamber, said projection also being provided with a perforation through its side, and an opening at the upper end of said recess, means for closing the perforations in the sides of the tubular lower part and the side of the recess, a horizontal arm extending from the valve-rod into said recess, an upwardly-extending rod secured to said arm, the upper end of which rod is screw-threaded, and provided with a suitable waste-valve, and passes through said opening in the upper part of said recess, substantially as and for the purpose set forth.
2. In a hydrant and street-washer having a waste-valve, as described, the combination, with the upper part of a longitudinal projection on the side of the lower part, of an inverted cup-shaped cover secured thereto by means of set-screws, and provided with downwardly and outwardly extending perforations, substantially as and for the purpose set forth.

In testimony that I claim the foregoing as my own I have hereunto affixed my signature in presence of two witnesses.

BENJAMIN F. COURTRIGHT.
